(57) **CLAIM**

The ornamental design for a laser beam-combining engine with fiber optic module, substantially as shown and described.

DESCRIPTION

FIG. 1 is a perspective view of a laser beam-combining engine incorporating the design and including a fiber optic module, an optional beam-shaping module, and locations for one, two, three, or four laser resonators;

FIG. 2 is a left-side elevation view thereof;

FIG. 3 is a back view thereof;

FIG. 4 is a right-side elevation view thereof;

FIG. 5 is a front view thereof;

FIG. 6 is a top view thereof;

FIG. 7 is a bottom view thereof; and,

FIG. 8 is another perspective view thereof.

The broken lines showing features of the engine form no part of the claimed design.
